UNITED STATES PATENT OFFICE.

FRANK H. GILLIGAN, OF WORCESTER, MASSACHUSETTS.

BRIDGE-WARNING DEVICE.

Application filed January 18, 1927. Serial No. 161,907.

This invention relates to a warning signal or safety device such as is used on railroads to indicate the near approach of an overhead bridge or other obstruction by which a brakeman or other employee on top of a car might be struck or injured. Such warning signals as heretofore commonly used have been found to be inoperative at times and deaths and injuries have resulted from the defects inherent therein.

It is the general object of my invention to provide an improved construction of warning signal or safety device for such purposes, so designed that it will be very reliable in operation and that the possibility of failure thereof will be substantially eliminated.

With this general object in view, one important feature of my invention relates to the provision of means by which the separate depending wires or "ticklers" are maintained at all times in operative position.

Another feature of the invention relates to the provision of means for preventing accidental loss or removal of any of the separate tickler wires.

My invention further relates to arrangements and combinations of parts which will be hereinafter set forth and more particularly pointed out in the appended claims.

A preferred form of the invention is shown in the drawings in which

Fig. 1 is a front elevation of two of my improved warning devices in operative position;

Fig. 2 is an enlarged partial side elevation of one of the warning devices shown in Fig. 1;

Fig. 3 is an end view of the safety device, looking in the direction of the arrow 3 in Fig. 2; and

Fig. 4 is an enlarged side elevation of a portion of one of my improved tickler wires and certain parts associated therewith.

Referring to the drawings, I have shown in Fig. 1 the general construction and operation of my improved bridge warning device. I have shown two warning devices W depending from suspension wires, cables or truss rods 10 and 11, secured to posts 12 firmly planted at the outer sides of the railroad right-of-way. Each of the warning devices W is centered over a line of track T. The height of the warning device above the rails varies according to circumstances,

and the lower ends of the depending elements of the warning devices always extend substantially below the lowest point of the bridge or other obstruction to be protected. 60 This general arrangement of bridge warning devices is in common use and my invention is directed to the construction of the warning device itself, rather than to the general combination and arrangement of parts 65 shown in Fig. 1 and above described.

Referring to Figs. 2 and 3, my improved warning device in the preferred form comprises a supporting bar 20, preferably of wood, which may be attached to the wires 70 or rods 10 and 11 by any suitable and convenient means. It is essential, however, that longitudinal displacement of the warning devices be prevented, so that each signal may remain accurately centered above its 75 track.

A plurality of tickler wires 21 are provided with loops or eyes 22 (Fig. 4) at their upper ends and are pivotally secured to screw eyes 23 which are firmly inserted in 80 the supporting bar 20. Each tickler wire 21 is also provided with a loop or eye 24 near the upper end of each wire and preferably about four inches below the eye 22.

A positioning member 25 is loosely inserted in the eyes 24, after the tickler wires 21 are assembled with the supporting bar 20. In the preferred form, the member 25 is constructed as a wire rod, extending loosely through the eyes 24 and having loops 26 90 at each end thereof to prevent longitudinal displacement of the member 25. While I prefer to form the member 25 as a wire rod, my invention is not necessarily limited thereto, and I may use more or less flexible 95 wire cable or other material having the necessary strength and resilience for the purpose. The length of the wires 21 will be regulated by operative conditions, the wires being frequently several feet in length. 100

Having described the construction of my improved bridge warning device, I will now point out the exceptional advantages thereof. When the device is in use, a brakeman standing on a car will be struck lightly by 105 a few of the wires 21, while the greater number of the wires are undisturbed. In the old construction (in which there was no equivalent to the member 25) the wires which struck the brakeman were frequently 110 thrown up against the supporting bar 20 and remained in raised position, thus leav-

ing an unprotected opening in the warning device at the very point where another brakeman would probably be standing. Numerous accidents have happened in which it appeared that the warning device was inoperative for this particular reason. With my improved construction, the positioning member 25 loosely connects all of the tickler wires so that no separate wires can be thrown up over the center and remain in raised position. The wires which are struck by the brakeman have a sufficient yielding movement relative to the remaining wires but cannot be displaced angularly sufficiently to throw them to inverted position.

A further advantage of my construction lies in the fact that it prevents accidental loss or removal of tickler wires. The positioning member 25, extending through the eyes 24 of all the wires 21, positively prevents any rotation of the wires or screw eyes 23, so that they cannot turn out of the supporting bar 20. Furthermore, if the bar 20 should become old and worn to such an extent that certain of the screw eyes were loose, even in this event the member 24 would retain the corresponding tickler wires in position and the device would remain wholly operative, unless the entire collection of tickler wires fell from the bar 20, a condition which would be immediately apparent and would be quickly remedied.

Having described my invention and the advantages thereof, it will be evident that changes and modifications can be made therein by those skilled in the art within the scope of my invention as set forth in the claims.

I do not wish to be otherwise limited to the details herein disclosed, but what I claim is:

1. A bridge warning device comprising

a supporting bar, a plurality of depending tickler wires pivotally secured to said bar, and a wire-positioning member effective to prevent substantial angular displacement of any tickler wire with respect to the remaining wires.

2. A bridge warning device comprising a supporting bar, a plurality of depending tickler wires pivotally secured to said bar, each of said wires having an eye formed therein and spaced below its point of pivotal connection, and a positioning member extending through all of said eyes and held from longitudinal displacement therefrom, said member being effective to prevent substantial angular displacement of any tickler wire with respect to the remaining wires.

3. A bridge warning device comprising a supporting bar, a plurality of depending tickler wires pivotally secured to said bar, each of said wires having an eye formed therein and spaced below its point of pivotal connection, and a positioning rod extending through all of said eyes and held from longitudinal displacement therefrom, said rod forming an auxiliary support for each of said wires.

4. A bridge warning device comprising a supporting bar, a plurality of depending tickler wires pivotally secured to said bar, and additional means effective to prevent accidental loss or removal of separate tickler wires from said warning device.

5. A bridge warning device comprising a supporting bar, a plurality of depending tickler wires pivotally secured to said bar, and means to secure said wires loosely to each other while permitting limited relative movement thereof.

In testimony whereof I have hereunto affixed my signature.

FRANK H. GILLIGAN.
